UNITED STATES PATENT OFFICE

MYRON H. RICHARDSON AND ALFRED D. ANTOINE, OF CHICAGO, ILLINOIS, ASSIGNEES
TO ADVANCE MACHINE COMPANY, OF CHICAGO, ILLINOIS, A CORPORATION OF
ILLINOIS

VENDING MACHINE

Original application filed June 23, 1924, Serial No. 721,661. Divided and this application filed June 15, 1928. Serial No. 285,655.

This application is a division of application, Serial No. 721,661, filed June 23, 1924, which has resulted in Patent No. 1,693,051, November 27, 1928.

5 This invention relates to vending machines, preferably of, though not necessarily limited to, the check controlled type, and one of the objects of the same is to provide an improved machine of this character embodying a plurality of containers for holding a supply of articles to be vended, and means whereby the articles in one of the containers will be maintained against delivery until the supply of articles in the other container has been exhausted, thereby constituting a reserve supply.

A further object of the invention is to provide improved means for ejecting or delivering an article from the machine and improved 20 means responsive in its operation to the operation of the ejecting means for controlling the delivery of the articles from one of the containers.

To the attainment of these ends and the accomplishment of other new and useful objects as will appear, the invention consists in the features of novelty in substantially the construction, combination and arrangement of the several parts hereinafter more fully 30 described and claimed and shown in the accompanying drawing, illustrating this invention and in which

Figure 1 is a vertical, longitudinal sectional view of a portion of a machine of this character constructed in accordance with the principles of this invention, with parts omitted for the sake of clearness.

Figure 2 is a plan view of the ejecting mechanism.

40 Figure 3 is a detail plan view of the controlling gate or member between the article containers or hoppers.

Referring more particularly to the drawing the number 15 designates a case or cabinet having a delivery outlet 16, through which the articles to be vended are delivered.

The cabinet is preferably provided with two holders or containers 17—18 for the articles and these holders are preferably in the 50 form of guides or hoppers separated from

each other but which have communication at their lower extremities. One of these hoppers or containers is arranged in advance of the other so that two columns of articles may be held within the machine. The articles are first delivered from the container 18 in a manner to be hereinafter set forth, and fall upon an inclined bottom 19 of the case 15, and when all of the articles have been delivered from the forward container 18, they will be supplied from the rear container 17. To that end there is provided a swinging gate or member 20 which is arranged beneath the open end of the container 17. This gate or member 20 swings about a suitable pivot 21 and is adapted to be moved so as to pass beneath the articles in the container 17 and support them to prevent them from being delivered from the machine and into the position shown in Figure 1, to prevent them from being delivered upon the operation of the ejecting mechanism and when the forward container holds articles to be delivered. After one article has been delivered the member 20 is moved from the dotted line position to the full line position so as to direct the articles from the rear container to a position to be ejected, when the supply of articles from the front container has been exhausted.

The ejecting mechanism consists of an ejector proper 22 which is slidable upon a suitable support 23, the ejector being preferably supported by means of members 24 shaped to engage over the lateral edges of the support 23. Connected with the ejector 22 is a frame like structure 25 into which the articles from the container 18 fall when the ejector is retracted, so that upon release of the article from the container 18, the article will fall into the frame like structure 25, which will have moved directly below the container, and so that the article will rest upon the support 23. When the ejector 22 is moved in a direction to deliver the article, the article will be engaged by the ejector and will fall from the frame like structure or portion 25 to be delivered through the outlet 16. The frame like structure 25 also serves as a means for holding the article upon the support 23, especially when cylindrical or round articles

to be delivered, as the walls of the frame like structure will prevent the article from rolling.

The member 20 is moved about its pivot 5 through the medium of the ejector 22 and to that end there may be provided spaced projections 26-27 between which an arm 28 that is connected with the member 20 and stands adjacent one of the walls of the frame like member 25, passes.

It will therefore be seen that by a reciprocating movement of the ejector 22 the member 20 will be moved about its pivot and having been raised to the dotted line position shown 15 in Figure 1, the weight of the articles in the container 17 will be overcome by reason of the arm 28 on the member 20 engaging the stop or projection 26 when the plunger is advanced.

Any suitable means may be provided for reciprocating the plunger, such as a pivotally mounted member 29, which is pivotally supported preferably intermediate its ends by means of the pivots 30, and one end of the 25 member 29 is connected with the ejector 22 in any suitable manner, preferably by means of the bifurcated extremity 31 engaging over a projection 32 connected with the ejector 22, preferably to the member 24, which in turn 30 is connected with the ejector. Obviously, one of these arms 29 and connecting means 31-32 may be arranged on each side of the ejector.

The member 29 is adapted to be moved about its pivot by means of a suitable cam shaped device 33 which is adapted to be rotated in a manner to be hereinafter described, and during its rotation the cam shaped portion 34 thereof will successively engage lugs or projections 35-36 carried by the member 29. When the cam 33 is rotated and assuming the parts to be in the position shown in 35 Figure 1, in full lines, the cam surface 34 will engage the projection 35 and will swing the member 29 about its pivot in one direction to move the ejector 22 in one direction.

When the cam surface 34 engages the projection 36 it will move the member 29 in the opposite direction so as to actuate the ejector 22 to deliver the article, it being understood 40 that the projections 35 and 36 are arranged on opposite sides of the pivot of the member 29.

The cam 33 is adapted to be actuated in any suitable manner, preferably by check controlled mechanism, preferably of the type and 45 construction as disclosed in United States patent to A. D. Antoine, No. 1,452,721, issued April 24, 1923, and therefore constitutes no part of the present invention.

Suffice it to say, however, that the check 50 controlled mechanism embodies a check carrier 37 having a check seat 38 therein. The check carrier is actuated by means of a suitable handle 39 located on the outside of the case 15 and the carrier 37 is adapted to be 55 rotated when a proper check is inserted in

the mechanism, until the carrier has assumed the position shown in Figure 1, at which time and under normal conditions a check deposited in the check carrier will be delivered from the check carrier. This check carrier mechanism, as before stated, constitutes no part of the present invention, as it is fully disclosed in the patent referred to.

When it is attempted to actuate the machine when the machine is empty, means are provided to return the check to the operator, and the means for thus accomplishing this end embodies a member 49 which is pivotally mounted as at 50 to a suitable support. Connected with the member 49, preferably to one end thereof as at 51, remote from the pivot 50, is a rock shaft or bar 52. One end 53 of this bar or member 52 is shaped to extend into the path of movement of the articles from the container 18 to the support 23. A spring 54 may be provided for shifting the member 49 in a direction to cause the portion 53 of the member 52 to be elevated above the support 23 so that when the ejector 22 is moved in one direction, the articles in their passage to the support 23, will fall upon the portion 53 of the member 52 and actuate the latter to swing the member 49 about its pivot against the stress of the spring 54.

The member 49 is provided with a finger or extension 55 which is adapted, in the normal position of the member 49, to assume a position adjacent the path of movement of the periphery of the check, while the latter is being carried by the check carrier and while seated in the check seat 39, or in the position shown in Figure 1. In this position the check will be held against delivery from the check seat by reason of the fact that it will be engaged by the finger or projection 55 of the member 49. If, however, this finger or projection 55 is retracted the check will fall from the check seat 38 and be delivered into the machine to set the machine into operation. The retraction of the finger or projection 55 is controlled, as before stated, by the articles in the container. It will therefore be manifest that when the container contains one or more articles to be delivered, the weight of the article when it passes to the support 23 upon the portion 53 of the member 52 will, as before stated, swing the member 49 about its pivot against the stress of the spring 54 to retract the member 49.

When the container is empty, no weight will be applied to the portion 53 of the shaft or member 52, with the result that the finger or extension 55 will be advanced or projected by the movement of the member 49 about its pivot 50 under the influence of the spring 54. Obviously the ejector 22 is so shaped that the reciprocation thereof will not be interfered with by the portion 53 of the member 52.

If desired the gate or member 20 may be

provided with a projecting portion or extension 20^a which, when the member 20 is moved into the position shown in dotted lines in Figure 1, will prevent the articles or packages in the container 17 from becoming wedged and will assist in supporting them.

Furthermore, as the member 20 is moved from the position shown in dotted lines in Figure 1 to the full line position, the extension or portion 20^a will engage and assist in ejecting the articles from the rear to the front compartment or container. This action is rendered possible because the member 20 will be positively moved about its pivot through the medium of the arm 28 being engaged by the lug 27.

It is thought that the operation of this machine will be clearly understood from the foregoing, but briefly stated it is as follows:

Assuming the parts to be in the position shown in full lines in Figure 1, and assuming the containers 17 and 18 to hold articles to be delivered, the operator rotates the handle 39 to rotate the cam 33, when a proper check 25 is inserted, and the rotation of this cam will move the ejector 22 in one direction so as to permit one of the articles to be delivered to the support 23 through the frame like portion 25 of the ejector. At the same time 30 that the ejector is being thus moved the gate or member 20 will be swung about its pivot from the full to the dotted line position, to prevent articles in the container 17 from being delivered therefrom. As soon as the 35 ejector 22 is moved in the opposite direction, one of the articles will fall upon the portion 53 of the member 52 to swing the member 49 about its pivot 50 and thereby retract the finger or portion 55 to permit the check to be 40 delivered from the check carrier 37. When the ejector 22 is moved in the opposite direction the article will be moved from the support 23 and will drop upon the support 19 to be delivered through the delivery opening 16. 45 In the event that there is no article in either of the containers 17 and 18, the finger 55 will not be retracted but will assume a position to prevent the check from being delivered from the check carrier.

While the preferred form of the invention has been herein shown and described, it is to be understood that various changes may be made in the details of construction and in the combination and arrangement of the 55 several parts, within the scope of the claims, without departing from the spirit of this invention.

What is claimed as new is:—

1. A vending machine including a container for the articles to be vended, said container including two compartments having communication adjacent the bottom, a pivotally mounted element adjacent the bottom of one of the compartments for supporting the 60 articles therein and for directing the articles

from one compartment into the other compartment, an ejector for ejecting the articles from the said other compartment, means for actuating the ejector, and an operative connection between the said ejector and the said element for actuating the latter. 70

2. A vending machine including a container for the articles to be vended, said container including two compartments having communication adjacent the bottom, a pivotally mounted element adjacent the bottom of one of the compartments for supporting the articles therein and for directing the articles from one compartment into the other compartment, means carried by said element and operating to eject the article from the last said compartment, an ejector for ejecting the articles from the said other compartment, means for actuating the ejector, and an operative connection between the said ejector and the said element for actuating the latter. 75

3. A vending machine including a container for the articles to be vended, said container including two compartments having communication adjacent the bottom, a pivotally mounted element adjacent the bottom of one of the compartments for supporting the articles therein and for directing the articles from one compartment into the other compartment, and an ejector for ejecting the articles from the said other compartment, the said pivotally mounted element being responsive in its operation to the actuation of the ejector. 80

4. A vending machine including a container for the articles to be vended, said container including two compartments having communication adjacent the bottom, a pivotally mounted element adjacent the bottom of one of the compartments for supporting the articles therein and for directing the articles from one compartment into the other compartment, an ejector for ejecting the articles from the said other compartment, means for actuating the ejector, an operative connection between the said ejector and the said element for actuating the latter, and means connected with the said element for engaging and assisting in forcing the article from one of the said containers. 105

5. A vending machine including a container for the articles to be vended, said container including two compartments having communication adjacent the bottom, a pivotally mounted element adjacent the bottom of one of the compartments for supporting the articles therein and for directing the articles from one compartment into the other compartment, an ejector for ejecting the articles from the said other compartment, means for actuating the ejector, an operative connection between said ejector and the said element for actuating the latter, and means connected with the said element for engaging and assisting in forcing the article from one of the 120 125 130 135

- said compartments, the last recited means also assisting in supporting the articles in the compartment at a predetermined time in the operation of the mechanism.
6. A vending machine including a container for the articles to be vended, said container including two compartments having communication adjacent the bottom, a pivotally mounted element adjacent the bottom of one of the compartments for supporting the articles therein and for directing the articles from one compartment into the other compartment, an ejector for ejecting the articles from the said other compartment, means for actuating the ejector, and an operative connection between the said ejector and the said element for actuating the latter, the said connection embodying a cam device connected with one of the parts and a projection on the other part against which the cam device operates.
7. A vending machine including a container for the articles to be vended, said container including two compartments having communication with each other adjacent the bottom, a pivotally mounted element adjacent the bottom of one of the compartments for supporting the articles therein and for directing and controlling the delivery of the articles from such compartment into the other compartment, a slidable ejector for the articles, means for actuating the ejector at will, a cam shaped arm connected with the said element and projecting therefrom, and means on the ejector for engaging said arm for rocking said element.
8. A vending machine including a container for the articles to be vended, said container including two compartments having communication with each other adjacent the bottom, a pivotally mounted element adjacent the bottom of one of the compartments for supporting the articles therein and for directing and controlling the delivery of the articles from such compartment into the other compartment, a slidable ejector for the articles, means for actuating the ejector at will, a cam shaped arm connected with the said element and projecting therefrom, and spaced projections on the ejector between which the said arm operates, said projections adapted to engage and move the arm to rock said element as the ejector is reciprocated.
9. A vending machine including a container for the articles to be vended, said container including two compartments having communication adjacent the bottom, a pivotally mounted element adjacent the bottom of one of the compartments for supporting the articles therein and for directing the articles from one compartment into the other compartment, a support beneath the bottom of the said other compartment for receiving the article to be ejected, an ejector for the article, said ejector having an opening therethrough
- through which the article passes to said support, means for actuating the ejector, and an operative connection between the said pivotally mounted element and the ejector.
10. A vending machine, including a container for the articles to be vended, said container including two compartments having communication adjacent the bottom, a pivotally mounted element adjacent the bottom of one of the compartments for supporting the articles therein and for directing the articles from one compartment into the other compartment, a support beneath the open bottom of the other compartment, an ejector having an opening therethrough, said ejector being movable to position the opening therein over the support and beneath the open end of the container to permit the article to pass from the container through said opening and on to said support, an operative connection between the pivotally mounted element and the ejector.
11. A vending machine including a container for the articles to be vended, said container including two compartments having a discharge outlet, a pivotally mounted element adjacent the bottom of one of said compartments for supporting the articles therein, an ejector for ejecting the articles, said element operating to direct the articles to a position to be delivered by the ejector, and means operating to cause the said element to be moved about its pivot upon each operation of the ejector.
12. A vending machine including a container for the articles to be vended, said container including two compartments having a discharge outlet, a pivotally mounted element adjacent the bottom of one of said compartments for supporting the articles therein, an ejector for ejecting the articles, said element operating to direct the articles to a position to be delivered by the ejector, and means whereby the ejector will positively move said element about its pivot upon each operation of the ejector.
13. A vending machine including a container for the articles to be vended, said container including two compartments having a discharge outlet, a pivotally mounted element adjacent the bottom of one of said compartments for supporting the articles therein, an ejector for ejecting the articles, said element operating to direct the articles to a position to be delivered by the ejector, and an operative connection between said element and said ejector whereby the said element will be positively actuated upon each actuation of the ejector.
- In testimony whereof we have signed our names to this specification on this 8th day of June, A. D. 1928.
- MYRON H. RICHARDSON,
ALFRED D. ANTOINE.
